UNITED STATES PATENT OFFICE.

DAVID MAXWELL, OF PARIS, ONTARIO, CANADA.

HARVESTING-MACHINE.

SPECIFICATION forming part of Letters Patent No. 235,548, dated December 14, 1880.

Application filed August 6, 1880. (No model.)

To all whom it may concern:

Be it known that I, DAVID MAXWELL, of the town of Paris, in the county of Brant, in the Province of Ontario, Canada, have invented certain new and useful Improvements 5 in Harvesting-Machines, of which the following is a specification.

My invention has relation more particularly to improvements in the raking mechanism of 10 reaping-machines of the class in which the rakes are arranged to roll upon a rake-arm when tripped to pass over the table without raking, and my improvements have for their 15 object the production of a simple, strong, and positively-acting tripping mechanism for harvesting-machines of the above-named class.

Referring to the accompanying drawings, Figures 1 and 2 are elevations, and Fig. 3 a plan, of a rake-head, in the construction of 20 which my improvements are embodied. Figs. 4, 5, and 6 are details of the rake-arm.

A is the standard, B the crown-wheel, C the pinion, and D the cam-plate, all constructed and combined substantially in the usual manner.

The rake-bars G are connected by the rake-heads to the rake-arms F. The rake-arms are hinged to the crown-wheel, and are coupled together by compensating-rods in the usual way, 30 so as to operate around the cam-plate with the required eccentric motion.

The rake-arms F are cored throughout their entire length for strength and lightness, and are provided with an offset at or about the 35 point of their connection with the rake-head, in order that the rake-bars G shall be supported at a proper position in relation to the table and rake-standard.

The rake-head is constructed in two independent sections, E² E³, each one of which is made independently adjustable on the rake-bar G by means of slots S and bolt T, in order that the separate adjustment of the rake proper to the table and of the friction-roller H to the 45 roller-track may be accomplished with accuracy and speed.

The rake-head section E² is provided with a socket, e, which is fitted upon the turned end of the rake-arm F, and secured thereto by 50 a pin and collar. The rake-arm is retained in

position by a spring, I, and stop-block P; but this connection, while sufficiently rigid for raking purposes, is flexible to the extent of allowing the rake to roll upon the rake-arm when the roller H strikes against the face of 55 the inclined gate J and pass over the grain-table without raking.

So soon, however, as the roller H begins to leave its track the spring returns the rake to its nominal position.

It will be observed that no locking trip, catch, stud, or bolt of any description, with their necessary complication of parts and fragility, is employed under this construction on the rake, but that the rake is retained in and 65 returned to position after displacement by a spring of a simple and lasting form.

The tripping mechanism consists of an upright post, K, which is supported in lugs formed on the gear-casing K', and is provided 70 with an arm, K², which overhangs the upper edge of the crown-wheel B. On the upper face of the crown-wheel a block, B', is provided. This block is arranged, as the wheel B revolves, to strike against and engage with the 75 arm K², turning the arm and post in their bearings, say, a quarter of a revolution, more or less. This movement of the post is utilized, by means of the crank K³ and rod K⁴, for the purpose of withdrawing the latch L, which holds 80

the gate J in the position shown in Fig. 1. So soon, however, as the block B' travels beyond the arm K² the arm, post, and latch are returned to position by the counterbalance-weight K⁵ connected with the latch, and the 85 latch is thus reset to receive the gate J. One or more blocks may be provided on the crown-wheel for the purpose of tripping the gate, and when it is desired to use more than one rake for raking purposes the blocks are made 90

of different heights, as shown in Fig. 2, so that by raising and lowering the post K the arm K² may be made to engage with one or more of the blocks and trip the gate accordingly.

The operation of rakes by the movement 95 of the gate arranged substantially as shown is well understood, and need not be described further than to say that the withdrawal of the latch L allows the gate to spring up, altering the line of travel of the next succeed- 100

ing rake, and causing it to pass over the table and operate as a rake, in its progress striking against a depending wing on the gate and setting the gate for the next rake. The 5 latch L can also be operated independently of the automatic devices by a rod connecting with a lever on the foot-board; and, if desired, the post K can be thrown out of working connection with the crown-wheel by elevating the 10 arm above all the blocks, and the raking be governed entirely by the operator.

It is obvious that the construction and manner of arrangement of the post K and projections on the crown-wheel can be altered and 15 modified without departing from the spirit of the invention, which is to trip the latch by the revolution of a projection formed at a suitable place on the crown-wheel.

I claim as new and desire to secure by Letters Patent—

1. A rake-arm for harvesting-machines, with the offset shown and described, tubular throughout its entire length, and cast in one piece, substantially as and for the purpose set forth.

2. A rake-arm, F, having an offset, as described, and rolling rake-head fitted to and swinging upon said arm as a bearing, and provided with a spring, I, and stop P, combined with a projecting stud in line with said rake, and armed with a roller, H, and a gate or guideway, J, whereby the rake G may be

caused to rotate on said rake-arm, for the purpose described.

3. A rake-arm for harvesting-machines, 35 having an offset, as described, and tubular throughout its entire length, and cast in one piece, in combination with a rolling rake-head fitted to and swinging upward as it turns upon the outer end of said arm, substantially as and 40 for the purpose set forth.

4. A rake-arm for harvesting-machines, cast in one piece, tubular throughout its entire length, and provided with an offset, and its outer end turned true and cylindrical, with a 45 rolling and swinging rake-head fitted to said cylindrical part, combined with the spring I and stop P, substantially as and for the purpose described.

5. A rake-head constructed in two sections, 50 E² E³, each one of which is independently adjustable on the rake by means of the slots S and bolt T, substantially as and for the purpose set forth.

6. The crown-wheel B, provided with the 55 projection B', the vertical rotating post K, having a laterally-projecting arm or offset, K², and the crank K³, combined with the rod K⁴, and counterbalance-latch L, and the gate J, substantially as shown and described.

DAVID MAXWELL.
